United States Patent Office.

THOMAS C. ROBINSON, OF BOSTON, MASSACHUSETTS, ASSIGNOR
TO GEORGE H. SANBORN, OF NEW YORK.

Letters Patent No. 92,368, dated July 6, 1869.

IMPROVED APPARATUS FOR CUTTING AND SHEARING METAL.

The Schedule referred to in these Letters Patent and making part of the same.

To all whom it may concern:

Be it known that I, THOMAS C. ROBINSON, of Boston, Suffolk county, State of Massachusetts, have invented a new and improved Hydraulic Metal-Cutter, for Cutting Wire, &c.; and I do hereby declare that the following is a full and exact description thereof, reference being had to the accompanying drawings, and to the letters of reference marked thereon.

The nature of my invention consists in a platform, with an upright frame, with which is connected a hydraulic press, with two cylinders and rams, actuated by a handle, cog-wheel, and rack, one of which rams carries a movable perforated plate, working with its face close against another fixed perforated plate, into which perforations metallic wires, rods, or bars being introduced, the motion of the said plate cuts the said bars, &c., off.

At the further end of the frame is another ram, which bears a half of a pair of shears, moving up against another fixed half above, for cutting sheet-metal; and at the side of the frame is a steam-cylinder, horizontally placed, with, opposite each end of it, a pump horizontally placed, and each actuated by a piston-rod from the steam-cylinder, these two pumps actuating, at pleasure, the two rams above described.

In the drawings annexed—

Figure 1 is a side view of my invention;

Figure 2 is an end view; and

Figure 3 is a section of fig. 1, at the line A A.

In the drawings—

B, fig. 1, is the platform.

C, fig. 1, is the frame.

D, figs. 1 and 2, is the upright pump.

E, figs. 1 and 2, is the piston-rod of the same.

F, figs. 1 and 2, is the upper portion of the piston-rod E, having one side of it fashioned to a rack.

G, fig. 1, is a cog-wheel, to one side of which is attached a handle, or lever, H, fig. 1.

On the left, in fig. 1, of the rack F, is a roller, I, borne by two ears, attached to the frame C, (seen in fig. 1,) upon which roller, one (the smooth) side of the rack F impinges.

The two ears are marked C^X C^X, fig. 2.

J, fig. 3, is the first ram-cylinder of the hydraulic press.

K, fig. 1, is the perforated fixed-rod cutter-plate. (The movable plate, actuated by the ram of the ram-cylinder J, is behind it.)

L, fig. 3, is the second ram-cylinder, whose ram bears the lower half, M, fig. 1, of a pair of shears, the upper half of the shears, N, fig. 1, being borne by the extreme right-hand portion of the frame C.

It is held by a shaft, O, fig. 1, projecting upward through the frame C, and is held in place by a wedge.

I am thus able to remove it at pleasure, and substitute for it a punch, whenever desirable.

Both the upper half, N, and the lower half, M, of the shears are capable of rotation.

P, fig. 1, is a steam-cylinder, horizontally placed, receiving steam, (or compressed air,) in any convenient method, and carrying within it a piston, with a double rod, (see fig. 3,) one, Q, fig. 1, projecting out of the cylinder to the right, and the other, R, fig. 1, to the left.

These piston-rods Q and R pass respectively into the pumps Q^X, fig. 1, and R^X, fig. 1, each of these pumps communicating respectively with the ram-cylinders J and L, opposite to which they are seen located in the drawing.

In fig. 3, there may be seen in section the two ram-cylinders and rams, the connecting-tube S S between the two, and a section of the steam-cylinder, and the two horizontal pumps.

And the operation of my machine is as follows:

When I wish to operate by hand, I, having my pumps duly charged with water, or other fluid, pass a rod, wire, or bar of metal, through one of the perforations (of appropriate size) in the plate K, and its mate, (beyond it.) Then, raising the handle H, I, by means of the cog-wheel G, (working in the rack F,) press down the piston-rod E, being assisted therein by the rotation of the roller I, into the pump D, thus causing the ram in the ram-cylinder J to ascend, carrying with it the movable perforated plate, (not seen,) mate of the fixed plate K. The sides of the perforations, (which I prefer to arm with steel bushings,) acting as shears, cut off the rod or bar, and the object of my device is accomplished; and the shears M N are actuated in the same manner by the handle H.

When I wish to cut a long piece of sheet-metal, I partially rotate the two halves of shears M and N till they are at right angles to the position shown in the drawing, fixing the blades in the desired position by means of the wedge shown above.

Another mode by which I operate my machine, is by means of the steam or compressed-air cylinder P, which, by means of its double piston-rod, (one emerging from each end, as seen in figs. 1 and 3,) actuates pistons in the pump-cylinders R^X and Q^X, each of these pump-cylinders actuating respectively the ram in the ram-cylinders, in front of which they are shown in the drawing.

I sometimes have another cog-wheel, rack, and lever-handle, for the sheet-metal cutter ram, all in the same machine.

Having thus fully described my invention, I do not claim separately the elements of the machine, but

What I do claim, is—

The improved hydraulic metal-cutter, constructed and operating in the manner described.
